UNITED STATES PATENT OFFICE.

WILLIAM H. SCHWEIZER, OF BALTIMORE, MARYLAND.

BUILDING BLOCK.

Application filed April 3, 1926. Serial No. 99,608.

This invention is a novel improvement in molded building blocks and the like, and the principal object thereof is to provide an integral moisture-proof building block, 5 molded or otherwise formed of concrete, cinders, or other plastic material, said block having three parallel walls, connected by integral webs at their ends and central portions, the middle wall being provided with 10 an insert or layer of material impervious to moisture, the impervious layer extending beyond the normal contour of the block at the top and one end face thereof, the opposite faces of the block being provided 15 with longitudinally disposed grooves to receive the adjacent projecting portions of the impervious layer on the adjacent blocks, when placed together to form a wall or the like, whereby moisture or dampness will be 20 prevented from passing through the blocks from the outer to the inner surfaces thereof, or along the mortar joints between the blocks, when assembled to form a wall or the like.

25 Other minor objects of the invention will be hereinafter set forth.

I will explain the invention with reference to the accompanying drawing which illustrates one practical embodiment thereof 30 to enable others to adopt and use the same, and will summarize in the claims the novel features of construction for which protection is desired.

In said drawing:

35 Fig. 1 is a perspective view of a complete molded block, detached.

Fig. 2 is a top plan view of a section of a wall constructed with my blocks.

40 Fig. 3 is an end elevation of a section of the wall shown in Fig. 2.

As shown in the drawings, each unit of the wall or the like, preferably comprises a substantially rectangular integral block made of concrete, cinders, or the like, in 45 the usual manner, said block having four rectangular openings A extending therethrough, adjacent the four respective corners of the block, whereby the block is divided into three parallel longitudinally disposed wall portions, B, C, D, connected together at their ends by webs E; and also 50 connected together at the transverse center of the block by webs F. The middle wall portion C has formed therein, during the 55 process of molding the block, an insert or

layer of material G which is impervious to water or moisture, which material G may be slag, moisture-proof cement, slate or any other similarly impervious material, layer G, as above stated, being formed in the 60 middle wall portion C, during the process of molding the block, in any desired manner.

The layer G preferably extends slightly above the upper face of the block as at G¹, 65 and also beyond one end face thereof, as at G². The bottom face of the middle wall portion C of the block in way of the layer G is longitudinally grooved as at C¹ to receive the projecting portion G¹ of the 70 block immediately below when the blocks are assembled in a wall or the like, as shown in Figs. 2 and 3. Similarly, the end face of the wall member C of the block opposite portion G² is provided with a vertically disposed groove C² in wall portion C, to receive the projecting portion G² of the 75 adjacent block when the blocks are assembled to form a wall or the like.

The projecting portions G¹, G², are each 80 provided with a series or row of holes or indentations G³ in their outer faces for the purpose hereinafter described.

In assembling the blocks in a wall or the like, mortar M is spread in the usual manner over the top and end faces of the blocks 85 on opposite sides of the projecting portions G¹, G², the projecting portions G¹, G², of one block entering into the recesses or longitudinal grooves C¹, C², in the adjacent 90 blocks. If any mortar, however, should enter the grooves C¹, C², when the projecting portions G¹, G² are inserted therein, such mortar will enter the holes or indentations G³ in the outer faces of the projecting 95 portions G¹, G², and allow the blocks to properly seat in order that the bearing on each block will be over its entire surface or area, the bearing being equally distributed over the entire surface or area of the block. 100

The projecting portions G¹, G², of the layer G, divide the mortar M, which is, of course, not impervious to moisture, between adjacent faces of the blocks so that no moisture can penetrate along the mortar line 105 past the layer G, from the exterior to the interior wall of the block.

Moreover, the extending portions G¹, G², of the layer G, when inserted in the grooves C¹, C², insure that the blocks will be erected 110

in perfect alignment, the portions G¹, G² preventing one block from sliding laterally of the other blocks.

I do not limit my invention to the exact form shown in the drawings for obviously changes may be made therein within the scope of the claim.

I claim:—

5 In a building block, an integral layer 10 of material impervious to moisture and pro-

jecting beyond two faces thereof, the opposite faces being correspondingly grooved, to receive the projecting portions of the adjacent blocks when assembled in a wall or the like each projecting portion of the layer 15 being provided with series of holes in its outer end, for the purpose specified.

In testimony that I claim the foregoing as my own, I affix my signature.

WILLIAM H. SCHWEIZER.
